LOCK NUT AND NUT PLATE

Charles C. Minfeldt, Glendale, Calif.

Application August 4, 1941, Serial No. 405,813

3 Claims. (Cl. 151—20)

My invention relates to lock nuts and lock nut plates, and more particularly to a lock nut which may be easily locked and easily unlocked, and which can be used repeatedly without deterioration of its locking qualities.

The main object of my invention is to provide a lock nut which may be repeatedly utilized, which is cheap to manufacture, and simple in structure.

Other objects of my invention will be apparent or will be specifically pointed out in the description forming a part of this specification, but I do not limit myself to the embodiment of the invention herein described, as various forms may be adopted within the scope of the claims.

In the drawing:

Fig. 1 is a plan view of a blank utilized for a single lock nut of my invention.

Fig. 2 is a view in elevation showing the blank of Fig. 1 folded to form a nut.

Fig. 3 is a cross-sectional view taken as indicated by the line 3—3 in Fig. 2.

Fig. 4 is a plan view of a modified blank.

Fig. 5 is an elevational view showing how the blank of Fig. 4 is folded.

Fig. 6 is a plan view of a blank for forming a plurality of lock nuts extending laterally from a single nut plate.

Fig. 7 is a view in elevation showing how the blank of Fig. 6 may be folded.

Fig. 8 is a sectional view taken as indicated by the line 8—8 in Fig. 7.

Fig. 9 is a plan view of a blank for forming a plurality of lock nuts attached to a single nut plate when the nuts are to be positioned over the nut plate.

Fig. 10 is a view in elevation showing the folding of the blank of Fig. 9.

Fig. 11 is a sectional view taken as indicated by the line 11—11 in Fig. 10.

Fig. 12 is an isometric view in cross-section of a hexagon nut made in accordance with my invention.

Referring directly to the drawing for a more detailed description of my invention, in Fig. 1 a blank is provided, preferably stamped out of sheet metal, this blank comprising a basal plate 1 and a lateral extension 2. As the blank is being cut, preferably in a die, a bolt aperture 3 and base attachment holes 4 may be cut therein. Lateral extension 2 is then folded on itself along a line indicated by the broken line 5 in Fig. 1, and these two folds are then folded over basal plate 1 along a line as indicated by the broken line 6 in Fig. 1. The lateral extension

is thus formed into oppositely extending folded portions, end portion 7 and a base portion 8. The folded portions 7 and 8 are then drilled coaxial with bolt aperture 3, and tapped with threads 12 to complete the lock nut, the completed nut being shown in Figs. 2 and 3. A discussion of the operation of the nut will be deferred until after the description of the various modifications illustrated.

In Fig. 4 for example, the lateral extending portion 2 may be provided with intermediate notches 9 at the ends of the fold between portions 7 and 8, and is also cut away at the ends of fold 6 by blanking junction notches 10 at the junction of the lateral portion with the basal portion. Such notching shortens the fold between the base 1 and basal portion 8 and the basal portion 8 and the end portion 7. The blank as shown in Fig. 4 is then folded in exactly the same manner as was indicated for the type of blank as shown in Fig. 1. The blank of Fig. 4 folded, drilled, and provided with threads 12 is shown in Fig. 5.

In Fig. 6 I have shown one manner by which 25 a plurality of nut elements may be formed integral with a nut plate. In this figure a continuous nut plate 11 is blanked with spaced attachment holes 4 therein and the bolt apertures 3 are formed in the extensions 2. The extensions in this case are one-third longer than in the embodiment of Fig. 1, so that when the folds are made as described for Fig. 1, the entire nut element will be offset from the nut plate as shown in Figs. 7 and 8. The nut plate may then 30 be fastened to a foundation member by means of holes 4 and the threads in the nut elements 35 may be used to hold bolts as desired.

In Fig. 9 I have shown a modification of the 40 nut plate shown in Fig. 6. In this case the lateral extensions 2 are formed as in Figs. 1 or 4 and the folds made to place the folded portions over the bolt apertures 3 which are now in alignment on the basal plate itself, positioned between attachment holes 4 as shown in Figs. 45 10 and 11.

Thus I have shown my device as capable of 50 being utilized as a single base plate and nut element or as a plurality of nut elements attached to a single base plate, with the nut elements either laterally extending from the base plate, or centrally positioned over the base plate. The nut element alone, without a base plate, this nut comprising only the folded portions 7 and 8, may 55 also be used as will be pointed out after explana-

tion of the manner by which the nut operates as a lock nut.

In using the nut, the basal plate 1 is attached to any foundation member by means of holes 4 so that the basal plate cannot rotate. When the lateral extension is folded, the folds are so pressed as to force the folded portions closely adjacent, but not necessarily touching each other. I prefer that the spacing between the folded portions, as indicated by dimension lines 13 in Fig. 3, be determined in accordance with the formula of .05 inch times the pitch of the threads that have been cut in the folded portions. I prefer, however, to limit the maximum spacing of the folded portions to a spacing not to exceed .0015 inch in order that the proper locking effect takes place.

After the basal portion 1 has been fastened to a foundation member and a bolt is started into the threads, the bolt first picks up the load on basal portion 8 of the double fold. The load will cause portion 8 to try to rotate, which it does slightly with relation to the end portion 7 of the nut element. As the load increases, portion 7 is also engaged with a twisting force sufficient to cause slight rotation thereof and closure of the small gap between the portions.

The gap, in accordance with the formula given above, is never more than sufficient to absorb the tolerance in the pitch diameter, thus applying friction to the threads, which grips the bolt. Furthermore, the portions 7 and 8 are neither twisted nor hingedly bent beyond the elastic limit of the metal; consequently any relative displacement will always be acting to apply locking forces to the bolt.

There is thus a large frictional force gripping the bolt, and holding the bolt so that it cannot easily loosen until extreme pressure is applied. As soon as the load is relieved by reversing the turn of the bolt, say one-eighth of a turn, the elasticity of the metal permits the two portions to realine themselves and the gap is always restored to its original condition. The bolt may thereafter be easily turned out of the threaded holes.

Inasmuch, therefore, as none of the locking ability of my nut is dependent upon any permanent distortion of the metal, due to the fact that this distortion is held within the elastic limit of the metal, the lock nut of my invention may be used over and over, until the threads are so worn that the nut would be useless as a nut in any event. Thus the nut of my invention is ideally adapted to be used in conjunction with materials which are required to be fastened together and locked, and thereafter easily unlocked and unfastened.

The modifications of my invention so far described, have all been nuts which have been provided with base plates which can be firmly attached to a foundation member. In Fig. 12, however, I have shown my invention formed as a hexagon nut. In this case all three portions 1, 8, and 7 of the nut are of equal size and preferably blanked and folded so that the folded structure defines a solid similar in shape to that of an ordinary nut. The aperture 3 in portion 1 is, as before, left without threads, and threads are formed in portions 7 and 8. Inasmuch as the basal plate 1 does not have threads, there is no tendency for it to turn because of directly

applied torsion of the bolt. Consequently, even though this portion is small it will, when the torque is sufficient on the bolt, hold tightly to and grip the foundation member through friction. Portion 1 can twist only to the extent of allowing the bolt to press against the edge of the hole that has been drilled to clear the threads. I have found that nuts made in this manner are very satisfactory even when additional features about to be described are not utilized in conjunction therewith.

However, in case that it is possible for raw material to be formed as well as blanked before being folded into the nut shape, I find that it is advantageous to form on member 1 a downwardly projecting boss 20 entering an elongated hole 21 in member 8. Likewise, the member 8 is provided with a downwardly extending boss 22, this boss entering elongated aperture 23 in base portion 1. This arrangement prevents either of the folds from rotating beyond a certain amount with respect to the adjacent fold, and will naturally not interfere with the practical application of the locking motion. However, bosses 20 and 22 prevent the folds from being relatively distorted by a wrench. Such a strain could occur if the wrench did not engage all three portions, might cause the folded nut to twist and tear at the hinge lines and might also strip the threads on one or both of the folds. However, by providing the bosses 20 and 22 and allowing them to project within apertures 21 and 23, I retain all the locking advantages of my construction, and at the same time prevent the nut from being damaged in case a wrench is applied to a portion only of the folded nut. Thus it can be seen that my invention is applicable to both free and fixed nuts.

I claim:

1. A lock nut comprising a basal portion having an aperture therethrough, and an integral extension thereto folded in reverse folds without projecting below the basal portion to form a series of layers with the end portion of said extension constituting the top layer, said layers having aligned threaded bolt receiving holes therethrough, said extension being unsecured to allow movement of the layers relative to the basal portion.

2. A lock nut comprising a basal portion having an aperture therethrough, an integral lateral extension intermediate the ends of said basal portion, said lateral extension being folded over itself and over the aperture in said basal portion without projecting below the basal portion to form a series of layers, the layers formed from said extension having aligned threaded bolt receiving holes, said extension being unsecured to allow movement of the layers relative to the basal portion.

3. A lock nut comprising a basal portion having an aperture therethrough, and an integral extension thereto folded in reverse folds to form a series of layers with the end portion of said extension constituting the top layer, said layers having threaded bolt receiving holes therethrough and a spacing between adjacent layers equal to substantially .05 times the pitch of the threads in said holes, said extension being unsecured to allow movement of the layers relative to the basal portion.

CHARLES C. MISFELDT.
